UNITED STATES PATENT OFFICE.

PURCHES MILES, OF BROOKLYN, NEW YORK.

WIRE LATHING.

SPECIFICATION forming part of Letters Patent No. 445,353, dated January 27, 1891.

Application filed October 1, 1889. Serial No. 325,670. (No model.)

To all whom it may concern:

Be it known that I, PURCHES MILES, a resident of Brooklyn, Kings county, and State of New York, have invented certain new and 5 useful Improvements in Wire Laths, Netting, Wire Fencing, and the Like, of which the following is a specification.

Heretofore wire lath, which usually consists of wire-cloth, has been stiffened by bars or 10 strips secured to the lath by metal clips or by weaving in. This stiffening is called "furring." It is expensive to apply the furring or stiffeners to the wire lath by means of clips, because, as far as I am aware, it has always been done 15 by hand.

The object of my invention is to so simplify and improve the connection between the stiffening-strips or furring and the wire-cloth as to materially reduce the cost of the wire lath 20 while improving the whole structure.

The invention consists in the combination, with the wire cloth or lath, of a stiffening-strip having a lip integral therewith, said lip being swaged or otherwise folded over a wire 25 of the cloth or lath, whereby the cloth and strip are secured together in a simple and effective manner.

Reference is to be had to the accompanying drawings, forming a part of this specification, 30 wherein—

Figure 1 is a face view of a piece of wire lath embodying my invention, part of the lath being shown covered with plaster. Fig. 2 is a detail cross-section on the plane of the line 35 *c c*, Fig. 1. Fig. 3 is an enlarged detail view of the stiffening-strip, showing a wire of the lath in position before the parts are finally connected. Fig. 4 is a similar view showing the strip and lath connected by swaging.

40 In the accompanying drawings, the letter *A* indicates a piece of wire lath consisting, essentially, of woven wire-cloth, upon which the plaster *B* is to be placed, as usual.

D is a stiffener or piece of furring secured 45 to the lath *A*, over which stiffener staples *E* are placed to hold the lath against the beams or other supports *a*. The stiffener or furring *D* consists of a bar or strip of suitable metal, which is shown as a narrow bar having un-

dulations or a series of curves or zigzags, 50 whereby when it is placed against a support *a* it will rest firmly and danger of its turning is avoided; but I do not confine myself to the cross-section of the stiffener shown, as the same may be square, oval, *U* or *V* 55 shaped, or of other form in cross-section; but I prefer the cross-section shown. The stiffener or furring *D* is placed against the wire lath *A*, preferably on edge, as shown, and portions of the stiffener are swaged or 60 otherwise folded over certain of the wires *b* of the lath *A*, whereby the lath and stiffener or furring are securely fastened together. In Figs. 1, 2, 3, and 4 the side or edge of the stiffener-strip *D* is provided with one or more 65 slots or recesses *d*, into which the wire *b* of the lath *A* is laid. (See Fig. 3.) The lips or edges *e* at the sides of the slot *d*, which are integral with the stiffener, are next swaged or turned over the wire *b*, so as to confine said 70 wire in the slot *d*, as clearly shown in Fig. 4. By this means the stiffener or furring is securely fastened to the wire lath without the necessity of using any separate pieces or clips, and the parts are not liable to become 75 separated. The stiffener *D* may be secured to the wire lath in as many places as desired, and the part *e* of the stiffener may embrace the warp of the wire-cloth, as in Fig. 1, or the weft may be embraced; or, if preferred, both 80 strands of wire may be secured at one point to the stiffener by the means shown.

One of the particular advantages of my improvement is that the stiffener can be quickly connected to the wire lath by machinery, whereby the cost of manufacture is greatly reduced, and the parts can be put together perfectly and evenly. The stiffener *D*, although shown as a flat narrow strip, may be of any desired shape and thickness. The 85 stiffeners serve to hold the wire lath at a proper distance from the beams *a*.

Having now described my invention, what I claim is—

A series of longitudinal wires and a series 95 of cross-bars contiguous thereto and extending at about right angles thereto, said cross-bars having recesses or slots extending at

about right angles to the length of the bars, and a lip or lips at the edge of each recess or slot, the corresponding longitudinal wires being placed in said recesses or slots in the cross-bars, and the lip or lips at the edges of said recesses or slots swaged or turned over

or upon said wires to rigidly bind the longitudinal wires to the cross-bars, substantially as described.

PURCHES MILES.
